ADJUSTABLE DAMPER

James D. McKnight, New York, N. Y.

Application March 12, 1930. Serial No. 435,076

9 Claims. (Cl. 98—110)

This invention relates to adjustable dampers employed in connection with heat and ventilating registers. It is particularly applicable to registers which are adapted to discharge a stream of 5 hot or cool air into a room or auditorium, or the like, although it may be used to advantage on registers intended for the removal of air as well. A common practice in connection with systems of this sort is to provide a series of louvers in 10 rear of the face of the register, these louvers being adjustable about their pivots to close off the delivery of air to the register to any extent desired.

One objectionable feature of such systems as 15 heretofore constructed is that the adjustment of the louvers to cut off the supply of air has at the same time served to alter the direction of the stream of air leaving the register. This has necessarily complicated the problem of properly 20 ventilating rooms provided with these systems. For example when the louvers are wide open, the current of air may be appropriately directed so as to avoid drafts on persons within the room but when the louvers are shifted to partially 25 close the register, the stream of air may be directed against a wall or the ceiling, or downwardly in such a way as to cause undesirable drafts.

It has been an object of the present invention to improve generally such adjustable damper systems and more particularly a system which is 30 free from the objectionable features now commonly found. According to my invention, the air delivered from the front of the register will always flow in the same direction, preferably in 35 a stream perpendicular to the face of the register, regardless of the adjustment of the device to regulate the quantity of air delivered. This materially simplifies the problem of arranging the registers for the proper heating and ventilation 40 of rooms. The stream of air always being directed in the same direction, the elimination of drafts may be effected once and for all. If upon installation of the system the air is directed away from the ceiling or the side wall, it will always be 45 directed away from these points regardless of the adjustment of the dampers.

Another feature of the invention is the provision of improved means for governing the quantity of air to be delivered from the register. The 50 arrangement is such that a fine variation in quantity may be effected between a completely closed condition of the damper to a wide-open condition. Furthermore, in effecting these variations the stream of air is maintained uniform over 55 substantially the entire face of the register.

Numerous other features and advantages of the invention will appear from the detailed description of the same which is to follow. While the invention is particularly applicable to the delivery side of a ventilating system, as above 60 explained, it has many advantageous features which are applicable as well to the intake end of the exhaust portion of the system. Certain admirable embodiments of the invention will now be described in detail in conjunction with the 65 accompanying drawings in which:

Figure 1 is a face view of a register embodying one form of the improved damper system, a part of the register face being cut away.

Figure 2 is a horizontal sectional view through 70 the register taken along the line 2—2 of Figure 1 and shows the dampers wide open.

Figure 3 is a horizontal sectional view along the line 3—3 of Figure 1 and shows the dampers in closed position.

Figure 4 is a diagrammatic view showing the movement of air through the register with the dampers partly closed.

Figure 5 is a diagrammatic view showing the action of the air when the dampers are fully 80 closed.

Figure 6 is a horizontal sectional view showing a portion of a modified damper construction with the dampers in closed position.

Figure 7 is a similar view with the dampers in 85 open position.

Figures 8 and 9 are diagrammatic views showing the movement of air through the modified damper system with the dampers fully and partially opened, respectively.

Figure 10 is a detail sectional view along the line 10—10 of Figure 2, and

Figure 11 is a detail sectional view along the line 11—11 of Figure 7.

Referring now to the drawings, and particularly Figures 1, 2, 3, and 10, there is shown a conventional form of register face 10 consisting of a grating of any suitable design. This register face may be secured in any suitable way to a frame 11 which may be of any appropriate form but is preferably rectangular. This frame supports and houses all of the damper mechanism to be described. It may be of any depth desired which is permissible within the limits available. Usually due to the wall construction in modern buildings it is impossible to employ a damper frame which is more than about 2 inches in depth. It is due to this limitation in space that development of a suitable damper 110

system of the type contemplated by the present invention has been made difficult.

The forward ends of the walls of the housing 11 may be turned at right angles to provide flanges 12 to which the register face 10 may be secured in any way as by means of rivets. At suitably spaced intervals between the side walls of the frame 11 there may be provided a series of vertical partition members 13 extending preferably in planes perpendicular to the face of the register. The partition members may be secured in the frame in any suitable way as by means of rivets serving to secure over-turned extensions 14 thereof to the top and bottom of the frame. At any suitable point the partition members may advantageously be provided with small recesses or depressions 15 extending vertically throughout their length for the purpose of providing seats for vertically extending shafts or rods 16. The latter may be secured in any suitable way in the top and bottom members of the frame 11. Hinged upon each of the rods 16 is an adjustable louver or vane 17 which, as shown in Figure 2, may assume a position substantially flat against the associated partition members 13 or, as shown in Figure 3, may assume a position completely closing off the openings between adjacent pairs of the vertical partitions.

For the purpose of adjusting the position of the louvers 17, each may have secured thereto an arm 18 which is pivotally connected to a link 19 which in turn is connected to a pivoted segment 20. The latter may be secured to one of the adjustable louvers 17 in lieu of an arm 18, as shown at the right of Figure 2. A worm 21 suitably mounted in brackets secured to the frame 11 may be rotated by means of a key applied to the square head 22 of the same for the purpose of adjusting the segment 20 to any desired position. It will be apparent that movement of the segment will bring about a corresponding movement of all of the louvers 17 to any position between that shown in Figure 2 and that shown in Figure 3. The louvers 17 may be entirely straight in cross section if desired or they may have a bent portion 23 adapted to co-operate with the adjacent partition member. The provision of the bent portion merely serves to limit the necessary movement of the louvers to completely close the register.

Referring now to Figure 4, there is illustrated diagrammatically the movement of the air through the system. Air delivered to the register through a duct 24 is advancing in a stream of substantially uniform velocity and extends over its entire area. That portion which is in line with the several louvers 17, as represented by the section designated *a*, will be turned back upon itself in the manner indicated and will not pass through the register. However, that portion of the air delivered over the area designated *b* will pass through this system between the partly closed louvers and the fixed vanes or partition members 13. In passing between these elements the air will expand to completely fill the space between adjacent partitions 13, and will pass out at the face of the register over the entire area designated *c* in a stream parallel to the partition members. If the louvers 17 are completely closed, as shown in Figure 5, then the entire air stream will be delivered into the pocket between the louvers and the associated partition members so that no air will pass through the register.

It will be apparent from the foregoing that the louvers will have a true valve action. Closing of

the louvers to any extent will produce a corresponding reduction in the flow of air past the louvers. Partial closing of the register will not simply result in an increased velocity of flow past the restricted portion of the passage as is commonly the case in prior structures. The velocity of movement of air through the restricted opening *b* remains the same so that the quantity of air permitted to flow is substantially directly proportional to the extent of the opening. It should be observed, furthermore, that the result of the arrangement of the louvers in the manner disclosed is to provide a compression chamber on the approach side of the vanes and an expansion chamber on the discharge side. Thus, even though air may be delivered to the register under a fair pressure, it will expand in passing through the restricted opening into the enlarged space on the discharge side and it will be delivered in an even flow over the entire register face. There will be no high velocity jets at scattered points as is so commonly the case in the prior structures. This permits easy balancing of a large ventilating system since the air may be delivered under sufficient pressure at a remote register to insure adequate supply. At the same time a register near the fan or blower may be throttled down to the point of passing only the required amount of air. The action of the compression and expansion chambers on the two sides of the louvers will be such as to produce a smooth distribution over the entire register face.

While reference has been made to the vertical disposition of the partition members 13 and louvers 17, it will be clear that the entire system may, if desired, be tilted through 90 degrees so as to place these elements in a horizontal position. This will have no effect whatever upon the control, since under the arrangement disclosed the stream of air will always emerge from the face 115 of the register in a path perpendicular to the face and over its entire area. This is a distinct advantage since in the employment of a long rectangular register, which may, for example, be 3 feet high and 10 feet wide, it is immaterial from 120 an operating standpoint whether the louvers are in a vertical or a horizontal position. However, from a manufacturing standpoint it is much simpler to employ a small number of long, horizontal louvers rather than a large number of 125 short, vertical louvers. With the older forms of construction, it is usually necessary to provide vertical louvers so that when adjusting the same the air stream will not be directed against the ceiling or down on the heads of persons in the 130 room. Should it be desired to direct the air stream at an angle to the face of the register, the fixed partitions may be tilted at a corresponding angle to such face.

Referring now to Figures 7, 8, 9 and 11, a modified form of construction is illustrated. Here, in lieu of having fixed partition members in the supporting frame, pairs of movable louvers are provided. For example there may be a series of louvers 25 adapted to co-operate with another 140 series of louvers 26, both series being carried by a plurality of vertically extending rods 27. Each of the louvers 25 may have secured thereto an arm 28 which is pivotally connected to a link 29 having a bent extension at its end which is pivotally 145 connected at 30 to a segment 31 mounted on a stud 310 extending from the bottom of the frame. Similarly, each of the louvers 26 may be provided with an arm 32 pivotally connected to a link 33 which is attached to the segment 31 at a 150

point 34 on the opposite side of the stud 310 from the point 30. A worm 35 carried by the frame and rotatable by means of a key applied to the square end 36 may serve to rock the segment 31 and carry the link 29 to the left and link 33 to the right of the positions shown in Figure 6. This, when carried to the proper extent, will result in shifting the series of louvers 25 and 26 into the full open position shown in Figure 7.

10 It will be obvious that when the louvers are in the positions shown in Figures 7 and 8, the stream of air will flow freely through the register as indicated by the arrows in Figure 8. However, when the louvers are partially closed, as indicated in Figure 9, the portion of the stream over the area designated *a* will be sent into the pockets between adjacent louvers 25 and 26 and will be turned back. The portion of the stream over the area designated *b* will pass through the openings between the louvers and will expand over the entire face of the register, as indicated by the arrows. It will be apparent that under all conditions the stream of air will be discharged perpendicularly to the face of the register. The 15 pivotal rods 27 may be located at a slight distance in rear of the register face, as shown, or, by a slight revision of the operating mechanism for the louvers, these rods may be shifted forwardly to a point just in rear of the register face. In the 20 arrangement shown, a stationary partition member may readily be provided between each of the rods 27 and the face of the register, either perpendicular to the latter or at any desired angle thereto to assist in the uniform direction of the 25 stream of air.

While preferred embodiments of the invention have been explained in considerable detail, it will be understood that many variations may be made in the general arrangement of the apparatus and 30 in the mechanism for operating the louvers without departing from the spirit and scope of the invention. When the damper system is to be used in connection with an exhaust register, it will be understood that the register face should 35 preferably be located on the opposite side of the casing 11 so that the air will still flow in the direction of the arrows indicated in Figures 4, 5, 8 and 9. The various terms employed herein have 40 been used merely for purposes of description and not for the purpose of imposing any limitations on the invention.

I claim:

1. In apparatus of the class described an air 45 conduit, a register having a face cooperating with the end thereof, a plurality of short fixed parallel vanes mounted in said register adjacent the end of said conduit to divide said register face into sections, and a plurality of adjustable vanes each pivoted adjacent and intermediate the edges of 50 one of said fixed vanes, said adjustable vanes extending from their pivots in a general direction opposite to the flow of air.

2. In apparatus of the class described an air 55 conduit, a register having a face cooperating with the end thereof, a plurality of short fixed parallel vanes mounted in said register adjacent the end of said conduit to divide said register face into sections, a plurality of adjustable vanes each 60 pivoted adjacent and intermediate the edges of one of said fixed vanes, said adjustable vanes extending from their pivots in a general direction opposite to the flow of air, and means for shifting said adjustable vanes to carry their free ends toward and away from the next adjacent fixed

vanes to vary the quantity of air passing through the register.

3. In apparatus of the class described a register having a face and a frame with walls substantially perpendicular to said face, a plurality of fixed vanes mounted at regular spaced intervals within said frame and extending to the face of said register, and a plurality of movable vanes mounted on pivots adjacent said fixed vanes intermediate the edges thereof, said movable vanes extending from said pivots in a direction away from the face of the register. 80

4. In apparatus of the class described a register having a face and a frame attached to and extending rearwardly from said face, a plurality of flat partition members extending rearwardly from said face, and a plurality of movable vanes each pivoted adjacent one of said partitions intermediate the edges thereof at a point near but spaced from said face, said vanes extending from their pivots opposite to the direction of flow through the register. 90

5. In apparatus of the class described a register having a face and a frame extending rearwardly from said face and connected therewith, two groups of vanes mounted within said frame, the vanes of one group being pivoted at one of their edges adjacent the vanes of the other group and having their outer ends movable toward and away from the vanes of said other group to close 100 and open the register, respectively, means for variably adjusting the ends of said pivoted groups of vanes, said vanes, when moved to a partially closed position, serving to form substantially V-shaped pockets at the pivots for retaining and preventing the passage of a portion of the medium flowing through the register, said pockets having their walls extending from the pivots in the direction from which the air is flowing. 105

6. In apparatus of the class described a register having a face and a frame extending rearwardly from said face and connected therewith, two groups of vanes mounted within said frame, the vanes of one group being pivoted at one of their 110 edges adjacent the vanes of the other group at a point near but spaced from said register face and having their outer ends movable toward and away from the vanes of said other group to close and open the register, respectively, said vanes 115 extending from said pivot opposite to the direction of flow through the register thereby, when moved to a partially closed position, serving to form pockets at the pivots for preventing the passage of a portion of the medium flowing 120 through the register.

7. In apparatus of the class described a register having a face and a frame extending rearwardly from said face and connected therewith, two groups of vanes mounted within said frame, all 125 of said vanes having a fixed pivot adjacent one edge, each vane of one group being pivoted adjacent a vane of the other group, and means for adjustably rocking the vanes of each group in unison in the same direction to any desired 130 extent, the vanes of different groups being rocked in opposite directions, said vanes being so constructed and arranged that when adjusted toward partially closed position they form pockets at the pivots having their walls extending from 135 said pivots in the direction from which the air is flowing to retain and obstruct the flow of a portion of the air. 140

8. In apparatus of the class described an air 145 conduit, flow control means disposed transversely 150

of said conduit, said means comprising a plurality of vanes arranged in pairs, the vanes of each pair having points thereon in fixed juxtaposed relation, and means for producing relative movement between other points on the vanes of a pair for regulating the quantity of air delivered through said register, said fixed points forming the apexes of substantially V-shaped pockets having walls extending from said apexes in the direction from which the air is flowing and into which a portion of the flowing air is directed, the vanes being arranged to provide an even distribution of the air at their adjacent ends.

9. In apparatus of the class described an air conduit, a register cooperating with the end of said conduit, means comprising a plurality of

pivoted vanes carried by said register adjacent the end of said conduit, adapted to continuously direct the air in a stream perpendicular to the face of the register, said vanes extending rearwardly of their pivotal supports toward the conduit, and means for adjusting said vanes to regulate the quantity of air delivered through said register, the vanes being so constructed and arranged as to form passages through the register all diverging toward the face of the register when the vanes are moved to partially closed position, the series of diverging passages having a combined area at their outer ends substantially equal to the area of the register face.
